ABSTRACT OF THE DISCLOSURE

A paper toy simulating an animal formed of a body piece foldable along predetermined lines to define a body portion and appendages such as wings which are movable relative to each other and the body portion when the toy is manipulated by hand.

This invention relates to toys and more particularly to a hand manipulated toy.

An object of this invention is to provide a new and improved toy in the form of an animal, such as a bird, which is easily manipulatable by one hand to simulate movement of the various portions of the animal.

Another object is to provide a toy which is easily formed of a minimum number of components.

Still another object is to provide a toy formed of flat pieces of resilient sheet substance, such as cardboard, which are foldable along predetermined lines to provide portions movable relative to one another.

A further object is to provide a paper toy simulating an animal, such as a bird, formed of a body piece foldable along predetermined lines to define a body portion and appendages, such as wings, which are movable relative to each other and the body portion when forces acting in predetermined directions are applied to the body portion. A still further object is to provide a toy wherein an operator piece or strip is secured to the body portion by means of which forces may be applied to the body portion to cause movement of the wings.

An important object is to provide a toy formed of flat sheet body piece foldable along predetermined lines to form a three dimensional representation of an object such as an animal.

Still another object is to provide a toy, of the type described wherein an operator member, also formed of a flat sheet piece, is secured to the body piece and is manipulated to cause movement of the portions of the body piece simulating the appendages of the animal.

Additional objects and advantages of the invention will be readily apparent from the reading of the following description of a device constructed in accordance with the invention, and reference to the accompanying drawings thereof, wherein:

FIGURE 1 is a perspective view of toy embodying the invention;

FIGURE 2 is a top view of the body piece of the toy before it is folded along the fold lines;

FIGURE 3 is a plan view of the operator piece of the toy;

FIGURE 4 is a side view of the toy;

FIGURE 5 is a front view of the toy showing the wings in their extended positions and showing the manner in which the fingers of the operator hold the toy;

FIGURE 6 is a view similar to FIGURE 5 showing the wings moved to their upper positions;

FIGURE 7 is a top view of another toy embodying the invention; and,

FIGURE 8 is a side view of the toy illustrated in FIGURE 7.

The toy 10, which represents a bird, is made of two flat blanks or pieces 11 and 12 of a suitable flexible

2

somewhat resilient material, such as cardboard or the like. The body piece includes a substantially oblong central portion 13 defined by the inwardly concave score or fold lines 14 and 15 which have substantially equal radii of curvature, a flat neck and head portion 16 which extends forwardly from the central portion and is defined by the score or fold lines 17 and 18 which extend forwardly from the front ends of the fold lines 14 and 15, and a rear or tail portion 19 defined by the inwardly convex arcuate fold lines 20 and 21 which extend rearwardly from the rear ends of the fold lines 14 and 15, respectively.

The body piece is bent upwardly at one side of the central portion along the continuous fold lines 14, 17, and 20, to cause the left side portion 24 of the body piece which represents the inner portion of the left wing 25 to extend at an angle of approximately 45 degrees from the left side of the central portion. The outer portion 26 of the left wing extends outwardly from the arcuate score or fold line 27 at an angle of slightly more than 90 degrees from the inner portion.

The upwardly extending left neck and head portion 30 of the body piece is bent upwardly along the fold line 17. Similarly the left rear side portion 31 of the body piece 11 is bent upwardly along the score or fold line 20 to represent the left side of the rear portion of the body and of the tail of the bird.

The right wing 25a, the right neck and head portion 30a, and the right tail portion 31a are similarly defined by and foldable along the score lines 15, 18 and 21, respectively. The right wing has an inner portion 24a and an outer portion 26a which is bent at an angle of slightly more than 90 degrees on the score or fold line 27a relative to the inner portion.

When the inner wing portions are folded upwardly along the inwardly concave fold lines 14 and 15, the central portion 13 of the body piece is bent resiliently into the upwardly convex position illustrated in FIGURE 4 due to the curvature of the fold lines 14 and 15. The inner wing portions 24 and 24a extend in arcuate planes due to the curvatures of fold lines 14 and 15 and 27 and 27a.

The operator piece 12 is of a substantially oblong shape and has a front end portion 32 which provides lateral tabs 33 and 34 foldable on the front end portion along the score or fold lines 35 and 36 and a similar rear end portion 37 which provides lateral tabs 38 and 39 foldable on the rear end portion along the score or fold lines 40 and 41. The fold lines 35 and 36 are spaced apart a distance substantially equal to or slightly shorter than the width of the front slit 42 of the body piece at the front end of the central portion and similarly the fold lines 40 and 41 are spaced apart a distance substantially equal to or slightly smaller than the width of the slit 43 of the body piece.

The operator piece 12 is assembled on the body piece by folding the tabs 33 and 34 flat on the front end portion 32 and then inserting the front end portion and the tabs upwardly through the slit 42 whereupon the tabs 33 and 34 move resiliently outwardly to substantially the positions illustrated in FIGURE 1 and the front end portion 32 lies flat against the top surface of the neck and head portion 16 of the body piece immediately forward of the slit 42. The tabs 38 and 39 are then similarly folded over flat on the rear end portion 37 of the operator member and the rear end portion 37 and the tabs are then inserted upwardly through the rear slit 43 whereupon the tabs 38 and 39 move resiliently to the positions illustrated in FIGURE 1 and the rear end portion 37 lies flat on the tail portion 19 rearwardly of the slit 43. Since the operator piece 12 is of greater length than the distance between the slits 42 and 43, the operator piece 12 then assumes the

downwardly convex or curved position illustrated in FIGURE 4. The tabs of the end portions 32 and 37 of the operator piece 12, since they extend angularly upwardly relative to the central portion 13, will now engage the edges of the body piece defining the inner edges of the slits 42 and 43 and thus prevent disengagement of the operator piece from the body piece.

The two pieces of which the toy is made are then in the positions illustrated in FIGURES 1, 4, and 5 so that the middle finger of a hand may be inserted in the transverse space or passage between in the central portion 13 of the body piece and the operator piece between its end portions 32 and 37, with the index finger located forwardly of the operator piece and engaging the forward surface 51 of the operator piece and with the ring finger located rearwardly of the operator piece and engaging the rear surface 52 thereof. If the operator now moves his middle finger downwardly relative to his index and ring fingers, the end portions 32 and 37 of the operator member are pulled inwardly toward each other thus causing the rear and front ends of the central portion 13 of the body piece also to be moved inwardly toward each other. Due to the upwardly convex curvature of the central portion 13 of the body piece, such inward movement of the opposite ends of the central portion 13 causes them to be moved downwardly as well as inwardly toward each other. The head and tail portions of the body are therefore moved downwardly relative to the central portion. In addition, since the central portion 13 is of substantially oblong shape, such inward and downward movements of the opposite ends of the central portion causes the wings 25 and 25a to be moved upwardly and toward each other. The various portions of the body piece are thus moved from the positions illustrated in FIGURES 4 and 5 to the position illustrated in FIGURE 6.

When the middle finger is then moved back upwardly to its initial position relative to the index and ring fingers, the body and operator pieces move resiliently back to their initial positions illustrated in FIGURES 4 and 5. The toy may thus be manipulated by means of one hand to simulate the body action of a bird during flight.

The body piece may, of course, be painted or colored in any suitable manner to represent a particular species of bird.

It will now be apparent that due to the curvature of the inner wing portions 24 and 25 between the fold lines 14, 15, 27 and 27a and the provision of the head and neck portions 30 and 30a and of the tail portions 31 and 31a, the toy provides a three dimensional effect when viewed from any angle.

It will further be seen that the toy may be easily formed of two flat pieces or blanks of a somewhat resilient substance, such as cardboard, which may be cut out along indicated lines from the side of a cardboard package, such as a cereal box, and then bent along the indicated fold lines to form the body and operator pieces which are then connectable by insertion of the end portions of the operator piece through slits which may be made in the body piece by a knife at indicated locations at the ends of the central portion thereof.

It will further be seen that the toy is easily mounted on and manipulated by one hand.

Referring now particularly to FIGURES 7 and 8 of the drawings, the toy 110 is similar to the toy 10 and, accordingly, its elements have been provided with the same reference numerals, to which the prefix "1" has been added, as the corresponding elements of the toy 10. The tail 119 of the toy 110 is formed of a separate piece whose forward portion is adapted to overlie the rear portion of the oblong central portion 113 of the body piece 111 and is provided with a slot 143a preferably of the same width as the rear slot 143 of the body piece. The rear end portion 137 of the operator piece 112, when its tabs 138 and 139 are folded flat thereon, is adapted to be inserted upwardly through the slots 143 and 143a of the body piece and the

tail, respectively, and its tabs 138 and 139 then move resiliently outwardly to substantially the positions illustrated in the drawings, the operator piece 112 thus securing the tail to the central oblong portion 113 of the body.

The front end portion 132 of the operator piece is similarly insertable through the front slot 142 of the central oblong portion when its tabs 133 and 134 are folded flat thereon. The tabs 133 and 134 then move resiliently outwardly to secure the front end portion from withdrawal through the slot 142.

The front and rear portions of the operator piece may be caused to move together to cause the wings 125 to move toward one another by placing the downwardly folded middle portion of the operator piece between the thumb and index finger of a hand so that the thumb engages the front surface 151 of the operator piece and the index finger engages the rear surface 152 thereof whereupon a slight pivotal movement of the thumb over the forefinger moves the two portions of the operator piece above the middle bent portion thereof toward one another thus pulling the front and rear end portions 132 and 137 of the operator piece toward one another. The opposite ends of the central portions are flexed downwardly and toward one another in this manner causing the wings to move toward one another. When the operator piece is then released, the resilient force of the central body portion of the body piece moves the wings back to their outer positions. The use of the body piece 112 whose central portion extends downwardly of the central body portion so that it may be grasped between two fingers, provides for a greater degree of flexile or bending of the central body portion and thus a greater range of movement to the toy.

It will be apparent that the middle portion of the operator piece 12 of the toy 10 could similarly be folded to be engaged between two fingers.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. A toy including: a body piece of resilient substance, said body piece having a longitudinally and upwardly arcuate central portion of substantially oblong configuration, and a pair of side portions extending divergently upwardly from opposite sides of said central portion, said body piece having transverse openings at the ends of said central portion; and an operator piece of resilient substance extending longitudinally below said central portion and having opposite end portions extending through said transverse apertures, said end portions having means engageable with said central portion for limiting downward movement of said end portions through said apertures, said operator piece between said end portions being of greater length than the distance between said transverse apertures whereby said operator piece curves downwardly below said central portion and defines with said transverse portion a transverse finger passage, said opposite ends of said central portion being movable inwardly and downwardly toward each other by means of said operator piece to cause said side portions to move upwardly toward each other.

2. A toy simulating a winged animal, said toy including: a body piece of a resilient substance, said body piece having a longitudinally upwardly arcuate central portion of substantially oblong shape, and side portions representing the wings of an animal extending divergently upwardly from inwardly concave fold lines defining opposite sides of said central portion, said side portions having inner and outer portions, said outer portions extending from said inner portions angularly outwardly along inwardly concave fold lines extending substantially completely across said side portions and spaced outwardly from and in nonparallel relationship with respect to said concave

fold lines defining opposite sides of said central portion; and an elongate operator piece of resilient substance extending longitudinally below said central portion, said operator piece being of greater length than said central portion whereby a middle portion of said operator piece is spaced downwardly of said central portion and connected to said body piece at opposite ends of said central portion.

3. A toy simulating a winged animal, said toy including: a body piece of a resilient substance, said body piece having a longitudinally and upwardly arcuate central portion of substantially oblong shape, a neck and head portion extending forwardly from the front end of said central portion, a tail portion extending rearwardly from the rear end of said central portion, and side portions representing the wings of an animal extending divergently upwardly from inwardly concave fold lines defining opposite sides of said central portion; and an elongate operator piece of resilient substance extending longitudinally below said central portion and connected to said body piece at opposite ends of said central portion.

4. The toy of claim 3 wherein said body piece has side portions extending upwardly along the sides of said tail and head and neck portions.

5. A toy simulating a winged animal, said toy including: a body piece of resilient substance, said body piece having a longitudinally and upwardly arcuate central portion of substantially oblong shape, and side portions representing the wings of an animal extending divergently upwardly from inwardly concave fold lines defining opposite sides of said central portion, said body piece having transverse apertures at opposite ends of said central portion; and an elongate operator piece of resilient substance and of greater length than said central portion extending longitudinally below said central portion and having end portions extending upwardly through said transverse apertures, said end portions having means engageable with said central portion at said apertures to prevent downward movement of said end portions through said apertures.

6. A toy simulating a winged animal, said toy including: a body piece of a resilient substance, said body piece having a longitudinally and upwardly arcuate central portion of substantially oblong shape, the neck and head portions extending forwardly from the front end of said central portion, a tail portion extending rearwardly from the rear end of said central portion, and side portions representing the wings of an animal extending divergently upwardly from inwardly concave fold lines defining opposite sides of said central portion; said body piece having transverse apertures at opposite ends of said central portion; and an elongate operator piece of resilient substance extending longitudinally below said central portion and having end portions extending through said slit to said apertures, said end portions having means engageable with said central portion limiting downward movement of said end portions relative to said central portion.

7. The toy of claim 6 wherein said body piece has side portions extending upwardly along the sides of said

tail and head and neck portions whereby said operator piece curves downwardly below said central portion and defines with said central portion a transverse finger passage.

8. A toy simulating a winged animal, said toy including: a body piece of a resilient substance, said body piece having a longitudinally and upwardly arcuate central portion of substantially oblong shape, the neck and head portions extending forwardly from the front end of said central portion, a tail portion extending rearwardly from the rear end of said central portion, and side portions representing the wings of an animal extending divergently upwardly from inwardly concave fold lines defining opposite sides of said central portion, said side portions having inner and outer portions, said outer portions extending from said inner portions angularly outwardly along inwardly concave fold lines spaced outwardly of said concave fold lines defining opposite sides of said central portion, said body piece having transverse apertures at opposite ends of said central portion; and an elongate operator piece of resilient substance extending longitudinally below said central portion and having end portions extending through said slit to said apertures, said end portions having means engageable with said central portion limiting downward movement of said end portions relative to said central portion.

9. A toy including: a body piece of resilient substance, said body piece having a longitudinally and upwardly arcuate central portion of substantially oblong configuration, and a pair of side portions extending divergently upwardly from opposite sides of said central portion, said body piece having front and rear transverse openings at the ends of said central portion; a tail piece having a transverse opening at one end thereof aligned with said rear transverse opening; and an operator piece of resilient substance extending longitudinally below said central portion and having one portion extending through said front transverse opening of said central portion and a rear end portion extending through said rear transverse opening of said body piece and through said opening of said tail piece.
